UNITED STATES PATENT OFFICE.

HOWARD H. JOHNSTON, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,373,077.

Specification of Letters Patent. Patented Mar. 29, 1921.

Application filed January 29, 1917. Serial No. 145,281.

To all whom it may concern:

Be it known that I, HOWARD H. JOHNSTON, a citizen of the United States, and a resident of Edgewood Park, in the county of Allegheny and State of Pennsylvania, have invented a new and useful Improvement in Control Apparatus, of which the following is a specification.

My invention relates to control apparatus and especially to the automatic interlocking of control drums, or the like, under predetermined conditions.

The object of my invention is to provide a relatively simple, compact and durable structure of the above-indicated character which shall allow intermittent movement in one direction only, in accordance with the remote control of a governing electric circuit.

More specifically stated, it is the object of my invention to provide a control drum shaft having a ratchet member provided with longitudinally-extending teeth and a coöperating normally disengaged rotatively stationary ratchet member for locking the drum shaft in certain positions, in accordance with current conditions in the main-motor circuit, for example.

My invention may best be understood by reference to the accompanying drawing, wherein Figure 1 is a view, in front elevation, of a control apparatus constructed in accordance with my present invention; and Fig. 2 is a diagrammatic view of a simplified control system utilizing the invention.

Referring to Fig. 1 of the drawing, the structure shown comprises a control drum MC, of any familiar type, which is suitably mounted upon a centrally located shaft 2 that extends through an appropriate bearing member 3 and preferably rests thereupon by means of a collar or shoulder 4; a circular ratchet member 5 having a plurality of teeth 6, the ratchet member being preferably detachably secured to the drum shaft 2, whereby ready replacements and adjustments may be effected; and a coöperating stationary circular ratchet member 7 having a plurality of longitudinally-extending teeth 8 that are arranged to engage the teeth 6 of the movable ratchet member 5.

The control drum MC may be used for the well-known purpose of governing the auxiliary circuits for a railway-motor control

system, or the like, through the agency of 55 suitable contact segments and control fingers.

The stationary ratchet member 7 is provided with a suitable centrally located shaft or rod 9 that is positioned in substantial 60 alinement with the drum shaft 2 and extends through an appropriate guide or bearing member 10 into an operating cylinder 11 of a familiar fluid-pressure operated device, to which compressed air or other suitable operating medium may be admitted through a pipe or passage 12. Since the air-cylinder 11 and the cooperating piston that is secured to the rod or shaft 9 may be of any well-known type, no further illustration or description thereof is deemed necessary, more 70 specially since my invention is not restricted to the use of an electrically-controlled, fluid-pressure-actuated mechanism.

The mechanical operation of the structure 75 just described, without regard to the electrical connections associated therewith, may be set forth as follows: In the illustrated normal position of parts, the control drum MC may be actuated in a "forward" or 80 clockwise direction, when viewing the control drum from above, as indicated by the arrow, and such movement is unimpeded until fluid pressure is admitted into the operating cylinder 11 to raise the stationary 85 ratchet member 7 into operative engagement with the rotatable ratchet member 5, whereupon the teeth 8 and 6 interlock to temporarily prevent further movement of the drum in the clockwise direction. When 90 fluid pressure is released from the cylinder 11, the control drum may be again actuated in the direction mentioned, until further interlocking engagement of the ratchet members is effected. Backward movement of the 95 control drum, that is to say, movement in a counter-clockwise direction, may be effected at any time during either the unlocked or locked position of the ratchet members, by reason of the relation of the teeth 6 and 8. Thus, the movement of the control drum in one direction may be intermittently arrested in accordance with predetermined conditions, whereas movement in the other direction is unrestricted at all times.

Reference may now be had to Fig. 2, wherein the system shown comprises an actuating coil 14 for governing the admission

of fluid pressure to the operating cylinder 11, and a control circuit for that coil, including a source of energy, such as a battery B, coöperating contact members of the master controller MC, and coöperating contact members 15 of a limit switch L of a familiar form.

The actuating coil 14 governs the position of a suitable needle-valve member for effecting communication between any suitable source of fluid pressure (not shown) and the operating cylinder 11, or for releasing fluid pressure from the cylinder to the atmosphere. Inasmuch as the construction just outlined is familiar to those skilled in the art, and, moreover, is not specifically essential to my present invention, no further illustration or explanation thereof is deemed necessary.

20 The limit switch L is of a well-known type wherein the actuating coil 16 is connected in series relation with the windings of a railway-vehicle motor or the like, to raise the movable contact member 15 into its upper or 25 operative position when the motor current attains a predetermined value and to allow the movable contact member to drop to its lower position to open an auxiliary circuit when the motor current has again decreased 30 below the predetermined value in question.

The operation of the control system may be briefly described as follows: Upon actuation of the master controller from its "off" position to an operative position *a*, a circuit 35 is completed from the positive terminal of the battery B through conductor 20, control fingers 21 and 22, which are bridged by contact segment 23 of the master controller, conductor 24, actuating coil 14 for the operating cylinder 11, conductor 25, the co-operating contact members of the limit switch L, when in its upper or high-current position, and conductor 26 to the negative terminal of the battery B.

45 Upon the energization of the actuating coil 14, the stationary ratchet member 7 is raised into engagement with the movable ratchet member 5, which, as previously described, is secured to the shaft of the master controller drum, thereby preventing further movement of the master controller MC until the limit switch L again drops to its lower position to open the circuit of the actuating coil 14, whereupon the stationary ratchet 50 member 7 recedes to its normal position, and further "forward" movement of the master controller is permitted.

I do not wish to be restricted to the specific structural details or arrangement of circuits herein set forth, as various modifications thereof may be effected without de-

parting from the spirit and scope of my invention. I desire, therefore, that only such limitations shall be imposed as are indicated in the appended claims.

65

I claim as my invention:

1. In control apparatus, the combination with a rotatable ratchet member, of a complementary ratchet member normally disengaged therefrom, and power-actuated means 70 responsive to predetermined electrical operating conditions for automatically moving said complementary member into engagement with said rotatable member to arrest movement thereof.

2. In control apparatus, the combination with a control-drum shaft, of a member rotatable with said shaft and having longitudinally-extending teeth, a member having complementary teeth and normally disengaged from said rotatable member, and means responsive to predetermined electrical operating conditions for automatically effecting operative engagement of the teeth of said members to arrest movement of said 75 rotatable member.

3. In control apparatus, the combination with a control drum shaft, of a member rotatable with said shaft and having longitudinally-extending teeth, a rotatively stationary member having complementary teeth and normally disengaged from said rotatable member, and remotely-controlled power-actuated yielding means responsive to predetermined electrical operating 90 conditions for automatically effecting operative engagement of the teeth of said members.

4. In control apparatus, the combination with a control drum shaft, of a member rotatable with said shaft and having longitudinally-extending teeth, a member having complementary teeth and normally disengaged from said rotatable member, and longitudinally-extending pneumatic means responsive to predetermined electrical operating 100 conditions for automatically effecting operative engagement of said members to prevent movement of said drum shaft in the one direction.

5. In control apparatus, the combination 110 with a rotatable ratchet member, of a complementary ratchet member normally disengaged therefrom, and means dependent upon predetermined electrical operating conditions for automatically effecting operative engagement of said ratchet members to prevent movement of the rotatable member in the one direction.

In testimony whereof, I have hereunto 115 subscribed my name this 20th day of Jan. 120 1917.

HOWARD H. JOHNSTON.
